EAR MUFF

Lawrence E. McDonough, Park Ridge, Ill., assignor to Maxant Button & Supply Co., Chicago, Ill., a corporation of Illinois

Application December 22, 1939, Serial No. 310,587

5 Claims. (Cl. 2—209)

This invention relates to an improvement in ear muffs and more particularly to an improved frame work upon which the ear muffs can be conveniently, easily and cheaply assembled.

5 An object of the invention is to provide an improved ear muff with a rigid metal frame which can be easily fabricated and readily assembled and which will permit the frame to be wholly concealed within the ear muff.

10 A further object of the invention is to provide an ear muff in which the frame is permanently secured together and to the fabric coverings so that the ear muff will not become disassembled in use.

15 A further object of the invention is to produce an ear muff in the form of a fabric envelope completely enclosing the frame work.

Further objects, capabilities, and advantages of the invention will appear from the following 20 description of a preferred embodiment thereof taken in conjunction with the accompanying drawings, in which:

Figure 1 is a perspective view of a pair of ear muffs;

25 Fig. 2 is a sectional elevation of one ear muff taken on the line 2—2 of Fig. 1 looking in the direction of the arrows;

Fig. 3 is a perspective view of one form of the retainer ring by which the assembled ear muff 30 is held in assembled condition, and to which is attached the ear by which the ear muff is secured to the flexible band which joins the pair of ear muffs;

Fig. 4 is a perspective view of the ear muff 35 frame;

Fig. 5 is a sectional elevation similar to Fig. 2 except that another form of the retaining ring is used;

Fig. 6 is a perspective view of the ear muff 40 frame and the retainer ring shown in Fig. 5 in position for assembly without the cloth being shown.

Fig. 7 is a perspective view of a modified form 45 of the annular frame shown in Fig. 4 in which the wall of the frame is notched to facilitate crimping the edge to form the frame into a channel;

Fig. 8 is a perspective view of a modified form 50 of the annular frame preformed into a channel;

Fig. 9 is a sectional view of the frame member shown in Fig. 8 taken on the line 9—9 of Fig. 8;

Fig. 10 is a sectional view comparable to Figs. 2 and 3 showing a modified form of the ear muff assembled without an inner liner;

55 Referring to the drawings, Fig. 1 shows a pair

of ear muffs, conventional insofar as the exterior is shown, consisting of two ear muffs attached by perforated ears to a flexible band 12. This band is composed of two adjacent flexible strips of metal, upon the one end of each of which is secured an ear muff 11, and upon the other end a ring 13, which provides a loop through which the other flexible strip may slide so that the flexible band 12 can be extended in length if desired to accommodate heads of different sizes. 10 The description thus far is of familiar structure which forms no part of this invention.

Each of the ear muffs of this invention is made of two sheet members which may be made of any suitable fabric, textile, cloth, fur or similar 15 materials. In this specification and claims such material will be designated by the term "fabric," regardless of whether fur or a true fabric or cloth is used. One of these is the outer covering 14, which in the drawings is shown as composed of 20 a piece of fur. The other is a lining member or liner 15, which is shown as made of a piece of cloth. The inner lining 15 should preferably be made of a soft cloth as it is in contact with the ear when the ear muffs are being worn.

The covering 14 and the liner 15 are cut into a strip of suitable size and shape to receive respectively the metal frame member 16 and retainer ring 20, and to permit the edges of the cloth to be turned over to overlap the body of the 30 cloth member sufficiently to cover the respective metal member.

Each ear muff is assembled about a ring frame 16, which is shown in perspective in Fig. 4. This frame in the preferred embodiment is shown as 35 a ring stamped and pressed from light sheet metal to form an annular ring with a horizontal base 17, and a vertical wall 18, so that the section of the ring forms a right angle.

Designed to be received by the frame 16 is the 40 retainer ring 20 shown in Fig. 2. This ring may suitably be formed of resilient wire, formed into a loop with the ends clipped together to form a bail to receive the perforated ear 21. The perforated ear 21 may be made from a strip of 45 metal bent over the retainer ring 20 to form a hinge as shown in Fig. 3. The strip is punched with the perforations 22 by which the ear muff is to be secured to the metal band 12.

As best shown in Fig. 2, the frame 16 is laid 50 upon the outer covering fabric 14, and the outer fabric is folded up over the upper edge 19 of the wall 18 of the frame member 16. The outer covering 14 should be sufficiently large so that it will overlap the frame 16 throughout its cir- 55

5 circumference. The fabric inner lining 15 is then laid over the retainer ring 20. This inner lining 15 is also sufficiently large that it overlaps the ring 20 throughout its entire circumference. It is to be noted that the ring 20 is generally of the same configuration as the frame 16 and is of such size that it may be embraced within the frame.

10 It is also to be noted as shown in Fig. 1, that the inner liner 15 is perforated to permit the passage of the perforated ear 21 therethrough.

15 When the retainer ring 20 has been covered with the inner liner 15, the covered retaining ring is brought within the wall 18 of the frame 16 and forced down until it rests upon the base 17 of the frame. Thereupon the upper edge 19 of the frame wall 18 is turned or crimped down so that the retainer ring 20 is firmly gripped within the frame 16.

20 The wall 18 of the frame 16 can be notched at intervals throughout its length to facilitate the crimping of the frame about the retainer ring. This modified form of frame is shown in Fig. 7, in which the wall 18 is cut with a series of notches 26 about its upper edge.

25 Similarly, the frame 16 can be preformed as an annular channel so that it has the configuration shown in Figs. 8 and 9 prior to the assembly of the structure, and then the retaining ring 20 within the inner liner 15 distorted and forced 30 within the walls 18, whereupon the bent over rim 19 of the frame 16 will retain the parts permanently in the relation shown in Fig. 2.

35 In Fig. 6 is shown an alternative form of retaining ring 20, in which the ring is made of a strip of metal, formed like the frame 16 of right angle section, and composed of the annular base 24 and the annular wall 25. One end of this retaining ring 23 is also provided with an ear 21 so that the two ear muffs may be fastened together with the flexible band 12. In the assembly of the frame 16 with the retaining ring of the type shown as 23 in Fig. 6, the process heretofore described for assembly of the structure is followed and the final step in this procedure is to turn or crimp down the rim 19 of the frame 16 40 in order that it may embrace the retaining ring 23 and maintain the parts in the relationship in which they are shown in section in Fig. 5.

45 When the ear muff of this invention is completely assembled, it is in the form of a fabric envelope, with the edges of the respective fabric members turned inwardly and lying adjacent to each other, where they are clamped between the frame and retainer ring.

5 A simpler form of the ear muff of this invention can be made without the inner liner 15. The frame may be any one of the forms shown in Figs. 4, 7, and 8. The outer covering 14 is applied in the manner hereinbefore set forth, and then the retainer ring 20 or 23 is immediately inserted, without being covered with the inner liner. The resultant ear muff would be of the construction suggested by the sectional view shown in Fig. 10. This form of the invention 10 is most satisfactorily employed when the outer covering 14 is of a thick soft or pile fabric or fur.

15 Having thus described my invention, what I claim as new and desire to secure by Letters Patent of the United States is:

1. An ear muff comprising a fabric envelope composed of two fabric sheets, the edges of said sheets being turned inwardly between said sheets, a frame member between one sheet and the in-turned edges thereof, and a retainer ring between the other sheet and the in-turned edges thereof, the in-turned edges of said sheets being clamped between said frame and said retainer ring.

2. An ear muff comprising an annular frame, an outer covering for said frame, an inner liner, 25 a retainer ring covered by said inner liner, and means upon said annular frame to retain said retainer ring snugly therein.

3. An ear muff comprising an outer covering having the edges turned inwardly and overlapping the covering a substantial distance, an inner liner having the edges thereof turned inwardly and overlapping said liner a substantial 30 distance, the overlapped edges of said inner liner and the overlapped edges of said outer covering 35 being adjacent to each other, a flanged annular frame within said outer covering between the body and overlapped edges thereof, a retainer ring within said inner liner between the body and overlapped edges thereof and seated within the annular frame.

4. An ear muff comprising an annular frame, a retainer ring within said frame, and an outer covering having the edges turned inwardly over said frame and firmly clamped between said frame and said retainer ring.

45 5. An ear muff comprising an annular frame, the upper edge of the wall thereof being notched at intervals about its length, an outer covering for said frame, an inner liner, a retainer ring covered by said inner liner, and means upon said notched wall to retain said retainer ring within said frame.

LAWRENCE E. McDONOUGH.
